UNITED STATES PATENT OFFICE.

JOSEPH S. WOOD, OF BROOKLYN, NEW YORK.

GAS APPARATUS.

SPECIFICATION forming part of Letters Patent No. 244,705, dated July 19, 1881.

Application filed December 17, 1880. (No model.)

To all whom it may concern:

Be it known that I, JOSEPH S. WOOD, of Brooklyn, in the county of Kings and the State of New York, have invented certain new and useful Improvements in Gas Apparatus, of which the following is a specification.

This invention relates to apparatus for making gas from hydrocarbon oils by the heat of a vapor-burner, which obtains its supply of gas directly from the generating-retort; and it relates more especially to certain improvements in the gas apparatus for which Letters Patent have been granted to me heretofore under date of June 15, 1880, and No. 228,848, with a view to simplifying the general construction and facilitating the manipulation of the same, so that it can be easily operated and more conveniently and reliably adjusted for any required number of lights.

The invention consists in the combination, with the generating-retort and its burner, of an exterior encircling-jacket, which is closed at the top and extended below the bottom of the retort, said jacket being provided with air-inlet openings at the bottom, with jet-openings for the burner-flame through the inner side below the retort-bottom, and with exit-openings for the gases of combustion through the outer side near the top.

The invention consists, further, in the combination, with a generating-retort having an exterior jacket with bottom air-openings and inlet and outlet openings for the burner-flame, of a heating vapor-burner supported below the retort by a gas-supply pipe.

The invention consists, further, of a regulator or gas-holder composed of a lower oil-reservoir, a middle gas-chamber having a regulating bellows-diaphragm, and an air-chamber above the diaphragm.

The invention consists, further, in the combination of certain parts, as hereinafter specified.

In the accompanying drawings, Figure 1 represents a vertical longitudinal section of my improved gas apparatus, and Fig. 2 is a vertical central section of a simpler form of the same.

Similar letters of reference indicate corresponding parts.

A in the drawings represents the vapor-gen-

erating retort, the bottom of which is connected by a vertical pipe, *a*, with a supply-pipe, *b*, leading to the oil-reservoir. In machines of smaller size which have to supply from ten to fifty lights the reservoir is arranged in the lower part of the regulator *B*, while in machines of larger size, supplying one hundred lights and more, the oil is preferably stored in a reservoir or tank outside of the building.

The oil-supply pipe *b* is provided with a stop-cock, *d*, for letting on or shutting off the supply of oil to the retort. The pressure on the oil is produced in the usual manner by means of compressed air, which is forced by an air-pump above the oil in the reservoir, so that the oil is delivered under pressure to the retort *A*. The retort is constructed with an exterior encircling-jacket, *A'*, which is closed at the top and extended below the bottom of the retort, so as to produce thereby a hollow space around the retort. The bottom of the jacket *A'* is provided with inlet-holes *e*, through which air is drawn to the inside of the jacket, while the flame from the burner *C* passes through holes *e'* of the inner wall of the jacket to the interior of the same, where it is mingled for thorough combustion with the atmospheric air drawn in through the bottom holes, *e*. The gases of combustion are conducted off through exit-holes *e''* of the outer wall of the jacket near the top of the same. The lower downwardly-extended part of the jacket *A'* serves not only for protecting the flame of the burner against accidental extinction by drafts, but, mainly, for dividing the heating flame into jets, which form a sheet of flame around the sides of the retort, so that the same is heated up from the sides as well as from the bottom. The jacket retains the heat and keeps up the regular and uniform working of the retort, which is an essential point in such machines.

The burner *C* receives its supply of gas directly from the retort by means of a short connecting-pipe, *f*. The burner *C* is started for heating the retort by means of an alcohol-cup, *f'*, as customary in vapor-burners. It is provided with two needle-valves, a horizontal valve, *g*, and a vertical valve, *g'*, the horizontal valve serving to regulate the supply of gas, while the vertical needle-valve *g'* regulates the

size of the flame. By the two needle-valves the flame of the burner is kept up steadily and uniformly without soot or smoke, and without any danger of being blown out, which, with one 5 valve only, would be the case, whatever be the pressure in the retort.

On the top of the retort is supported the horizontal valve-cylinder D, with its needle-valve D'.

- 10 At the forward end of the valve-cylinder is arranged the mixing-chamber E, which is connected by a narrow orifice with the valve-cylinder. The mixing-chamber E is provided with an air-port, h, and with a narrow discharge-throat, h', from which the mixed oil-vapors and air pass through a connecting-pipe, h², to the regulator B. The regulator or gas-holder B is made of cylindrical shape, of a size proportioned to the number of lights to be supplied 15 by the machine. The regulator B is made of iron and divided, in machines of smaller size, into three parts, which are screwed together. The lower part, B', is separated by a solid partition-plate, i, from the middle part or gas-chamber, B², proper. The lower chamber, B', serves as the oil-reservoir, and is provided with an inlet-tube and screw-cap, i', for filling the reservoir, and with an air-cock, i², for the admission of compressed air. The middle part 20 or gas-chamber, B², is connected by the pipe h² with the injector-mixer D E, and also, by a pipe, i³, with the service-pipe. The gas-chamber B² is further provided with a stop-cock, i⁴, near the partition-plate i, for drawing off the 25 condensation, which may be conducted back into the reservoir B', as shown in Fig. 2. The third or air chamber, B³, is formed above the gas-chamber B² by a movable dividing-diaphragm, B⁴, which is connected by a bellows-shaped side portion, B⁵, of leather or other 30 flexible material, with the exterior wall of the regulator. The diaphragm B⁴ is attached to a central stem, l, which is guided in a socket-tube, l', of the horizontal partition-plate i and 35 an opening of the top plate or cover of the regulator, so that when the pressure of gas supplied to the gas-chamber increases the diaphragm is raised by the expansion of the bellows-shaped side portion, B⁵.
- 40 The top or cover of the air-chamber B³ is secured by a circumferential flange and fastening-screws to the wall of the regulator in such a manner that a small annular space between the wall and flange is formed through which, 45 upon the raising of the diaphragm, the air can slowly pass out, without exerting thereby too great a pressure upon the diaphragm and interrupting the working of the same. By the slow escape of air a regulating air-cushion 50 above the diaphragm is formed, which exerts a certain pressure thereon, and which secures the smooth and reliable working of the diaphragm without jar or strain.

To the upper exterior end of the stem l of 55 the diaphragm is attached, by a clamping-screw, l², a sleeve, m, which carries, in side brackets or ears, m', a vertical adjusting-screw,

n, that is provided between the ears m' with an annularly-grooved nut, n', to which the forked end of the longer arm of a fulcrumed 70 elbow-lever, D², is applied. The shorter arm of the elbow-lever D² is secured by a set-screw to the slotted outer end of the needle-valve D' of the valve-cylinder D. By raising or lowering the adjusting-screw n the longer arm of 75 the elbow-lever is raised or lowered and the needle-valve of the valve-cylinder moved forward or backward, so that the outlet-orifice of the same is contracted or enlarged, and thereby the generation of gas for any number of 80 lights regulated in a reliable manner. When the needle-valve is thus adjusted the supply of gas for the required number of lights is kept up automatically by the regulating action of the bellows-diaphragm B⁴. If the lights are 85 to be entirely extinguished the screw n is turned up until the needle-valve D' closes the valve-orifice entirely, the heating-flame of the burner C being also turned down small, so that only sufficient gas is generated in the retort to 90 supply the heating-flame and keep the same ready to generate gas whenever required without necessitating the reheating of the burner by alcohol.

In all gas-machines heretofore in use the gas-holder, and with it the regulating-lever, rise until a certain height is reached, when the valve is closed entirely, and the generation of gas interrupted. The gas-holder falls, then, again, and opens the valve entirely, which rise 100 and fall, together with the closing and opening of the valve, take place alternately. The action of the generating-retort is, therefore, not continuous, but intermittent, which is objectionable.

By the construction described the needle-valve is never entirely closed, consequently a continuous working of the retort is kept up. The adjusting-lever rises when any number of lights are extinguished, and falls when a larger number are lighted, the rising and falling of the lever opening the needle-valve more or less, but without entirely closing the same. The lever also falls on the decrease of pressure in the oil-tank, upon the consumption of oil 115 or other causes. This secures a continuous generation of gas and not an intermittent one, as heretofore, which is a most important feature for the successful working of this class of gas-machines.

By the improved construction of the retort and its heating vapor-burner the gas apparatus is kept in operation in the most economical manner without danger of interruptions, while by the improved regulating mechanism of the 125 gas-chamber and needle-valve a uniform pressure and supply of gas is furnished for any number of lights. The gas apparatus is thrown into or out of operation without difficulty, and can be attended to by any one without the 130 least inconvenience or danger.

A very simple, compact, and portable form of gas-machine for a smaller number of lights is obtained by dispensing with the automati-

cally - regulating lever mechanism and dia-phragm of the gas-chamber, and adjusting the apparatus simply by the needle-valve of the injector-mixer to the number of lights required, 5 as shown in Fig. 2.

In case the combination of the reservoir and gas-chamber should not be desired, they can be separated and the former placed outside of the building, in which case the gas-chamber 10 and generating-retort take up still less space, and can be put up at any convenient place.

Having thus described my invention, I claim as new and desire to secure by Letters Patent—

1. In a gas apparatus, a generating-retort, 15 A, having an exterior encircling jacket, A', which is closed at the top, extended below the bottom of the retort, and provided with bottom air-openings, e, inner openings, e', and outer openings, e², substantially as specified.
2. In a gas apparatus, the combination, with 20 a generating-retort having an exterior jacket with bottom air-openings and inlet and outlet

openings for the burner-flame, of a heating vapor-burner supported below the retort by a gas-supply pipe, essentially as specified. 25

3. In a gas apparatus, a regulator or gas-holder composed of a lower oil-reservoir, a middle gas-chamber having a regulating bellows-diaphragm, and an air-chamber above the diaphragm, substantially as set forth. 30

4. In a gas apparatus, the combination of the bellows-diaphragm B⁴, having vertical guide-stem l, sleeve m, having ears m', adjusting-screw n, annularly-grooved nut n', and connecting elbow-lever D², having forked outer 35 end, substantially as set forth.

In testimony that I claim the foregoing as my invention I have signed my name in presence of two witnesses this 15th day of September, 1880.

JOSEPH S. WOOD.
